CLAIM

We claim the ornamental design for a pet food container, as shown and described.

DESCRIPTION

FIG. 1 is a right perspective view of a pet food container showing our new design;

FIG. 2 is a top plan view thereof;

FIG. 3 is a bottom plan view thereof;

FIG. 4 is a left side view thereof, the side opposite being a mirror image thereof;

FIG. 5 is a front view thereof; and,

FIG. 6 is a rear view thereof.

1 Claim, 6 Drawing Sheets

FIG. 1

FIG. 2

FIG. 3

FIG. 4FIG. 5

FIG. 6
